UNITED STATES PATENT OFFICE.

FRANK F. BEEBY, OF CHICAGO, ILLINOIS, ASSIGNOR TO CEMENT-GUN CONSTRUCTION COMPANY, OF CHICAGO, ILLINOIS, A CORPORATION OF ILLINOIS.

PROCESS OF CONSERVING AND REPAIRING CHIMNEYS.

Application filed November 24, 1919. Serial No. 340,315.

To all whom it may concern:

Be it known that I, FRANK F. BEEBY, a citizen of the United States, residing at Chicago, in the county of Cook and State of Illinois, have invented a certain new and useful Improvement in a Process of Conserving and Repairing Chimneys, of which the following is a specification.

My invention relates to a process of conserving and repairing chimneys, and more particularly to concrete chimneys built about steel stacks already in place. My chimney is particularly adapted to be constructed by the projection of the type of concrete called gunite against the outer surface of the chimney, which surface acts as a base against which the cement hardens. Further purposes will appear from time to time in the course of the specifications.

I illustrate my invention more or less diagrammatically in the following figures wherein:

Figure 1 is an elevation of my chimney with parts broken away;

Figure 2 is a plan view of the anchorage of my chimney;

Figure 3 is a section on the lines 3—3 of Fig. 1;

Figure 4 is a section on the lines 4—4 of Fig. 1;

Like parts are represented by like symbols in all of the figures. A is any suitable base or supporting structure to which a steel chimney A¹ is attached. A² are anchor bolts, fixed in the base A and securing with the nuts A³, the members A⁴ which anchor the enlarged base of the steel chimney to its foundation. I employ this structure as an anchorage for my concrete chimney reinforcement. A⁵ are angle irons or any other suitable structural members secured to the members A⁴ by the bolts A² and nuts A³ and A⁶ are channel irons suitably secured to A⁴, and extending about the chimney. B are vertical reinforcing bars which may be hooked about and wired to the irons A⁴, or, where the length of the bar below the channel gives sufficient anchorage, may merely be grounded on the base A. B¹ are horizontal circular reinforcing bars or bands, spaced along and secured to the bars B, in any suitable manner, as is common in reinforced concrete structures. B² is reinforcing netting or mesh disposed in one or more

layers throughout the chimney structure. C 55 is the gunite or concrete in which the reinforcement is imbedded.

My method of construction is as follows: I build my concrete chimney about a steel stack which is weakening or leaking, or for 60 any other reason, needs strengthening or replacement. The steel stack serves as centering for the reinforcement, and acts as the base or mold against which the concrete is shot.

Steel stacks are firmly anchored to their foundations by anchor bolts imbedded in the masonry or concrete, which clamp the base of the chimney in place. I use these anchor bolts as the anchorage for my reinforcing 70 structure. In the drawings, I illustrate a specific form of anchorage, but it will differ from stack to stack, and my invention is in no sense limited to the details of anchorage and reinforcement shown. In the illustrated form I secure channel irons to the anchor bolts, and use them as the anchorage of the concrete stack.

The reinforcement is the combination usual in the art of vertical rods, horizontal 80 rods or hoops, wired to the verticals, and wire or expanded metal mesh. The vertical rods may be grounded on the foundation as in the illustrated form, or may be hooked about, or otherwise firmly secured to the 85 structural members about the base of the stack. If the length of the bar below the channel structural member is considerable, it will be sufficiently anchored by the concrete to obviate the necessity of looping or 90 hooking it about the member. The reinforcing structure is spaced from the stack by any suitable means, such as wooden blocks which can be removed from any one point before it is reached by the level of the gunite. 95 The reinforcing structure will thus be entirely out of contact with the stack, and cannot be attacked or rusted by gases or weather.

When the reinforcement is in position, 100 the stack may be shot by the well known gunite process, which consists in the projection against the stack of a thin cement, commonly called gunite, shot from a pressure nozzle manually manipulated.

If necessary, the thick portion of the concrete, about the base of the stack, may be poured into a mold. I prefer to construct

the rest of the stack by projecting gunite against the steel stack until the reinforcement is covered to the desired thickness.

I build a scaffolding about the stack, but 5 out of contact with it. In practice two gangs will work from the scaffolding, one, highest up, placing the reinforcing structure, and cementing it as, for example, with wooden blocks, and another, below manipulating the cement guns or nozzles. As the 10 level of the cement rises the wooden centering is removed. There is of course no fixed relation between the crews, and the whole structure might be put in place before the 15 cement gunning begins. In practice the cement projection will generally follow fairly closely the construction of the reinforcement.

When the cement is all in place, and has 20 hardened, the function of the steel stack ceases. It is surrounded by reinforced concrete stack, which will not be affected by the progressive disintegration of the steel stack.

I claim:

25 1. The process of constructing about a chimney already in place a second chimney which consists in placing reinforcing about such first chimney, spacing the same from such chimney, mounting such reinforcement upon a foundation at the base of such

chimney anchoring said reinforcement to said foundation and placing upon and about such reinforcing and about such first chimney concrete to form such second chimney.

2. The process of constructing about a 35 chimney already in place a second chimney which consists in placing reinforcing about such first chimney, spacing the same from such chimney, mounting such reinforcing upon a foundation at the base of such 40 chimney and placing upon and about such reinforcing and about such first chimney concrete to form such second chimney.

3. The process of forming a substitute 45 chimney about an existing chimney, which consists in erecting a reinforcement about said chimney, inserting spacing members between said reinforcement and said existing chimney, applying concrete about said chimney and said reinforcement to the position of the spacing members, removing said spacing members and applying concrete to the next higher portion.

In testimony whereof, I affix my signature in the presence of two witnesses this 55 19th day of November 1919.

FRANK F. BEEBY.
